UNITED STATES PATENT OFFICE.

JOHN SCHURMAN, OF HIGHLAND PARK, MICHIGAN.

PARTITION.

Application filed March 5, 1921. Serial No. 449,809.

To all whom it may concern:

Be it known that I, JOHN SCHURMAN, a citizen of the United States of America, residing at Highland Park, in the county of Wayne and State of Michigan, have invented certain new and useful Improvements in Partitions, of which the following is a specification, reference being had therein to the accompanying drawings.

- 10 The invention relates to partitions and has for its main object the provision of a good looking substantial partition in which the wall panels, windows and doors can be readily removed and replaced, or the whole 15 partition taken down and rebuilt or reset in other locations without in any way being damaged or destroyed. The invention is particularly applicable to office buildings, the partitions of which are changed to suit 20 the tenant, and also to factories. Another object of my invention is to provide a mullion having sections which are engageable with standard window sashes, with door jambs which also can be made standard, and 25 with wall panels which can be formed of metal, asbestos board, plaster or wood. A further object is the provision of a mullion of substantial I-cross section which is formed by its cooperating channel shaped 30 sections having their webs adjacent to each other, there being sufficient space within the mullion for electric wires and the like, which space is accessible by means of a removable cover plate. Other objects of the 35 invention reside in the novel features of construction and combinations and arrangements of parts as more fully hereinafter set forth.

In the drawings:

- 40 Figure 1 is a side elevation of a portion of the partition embodying my invention and showing intersecting mullions;

Figures 2 and 3 are respectively, cross sections on the lines 2—2 and 3—3 of Figure 1;

- 45 Figure 4 is a cross section on the line 4—4 of Figure 2;

Figure 5 is a cross section through the partition near the floor;

- Figure 6 is a cross section similar to Figure 2 and showing the mullions engaging panels formed of different material.

The partition as shown in Figure 1 comprises the horizontal and vertical mullions 1 and 2 respectively which are engageable 55 with the partition members such as the wall panel 3, the window sash 4, and the door

jamb 5. The mullions 1 and 2 are identical and each comprises the cooperating sections 6 and 7 which are of substantial channel cross section and have the parallel side 60 flanges 8 and 9 and the connecting web 10, the webs extending adjacent to each other, the arrangement being such that the two sections form a mullion which is of substantially I-cross section and is therefore very 65 strong. Extending longitudinally of the webs 10 of the section 7 is the series of elongated apertures 11 through which extend the tongues 12 struck out from the web 10 of the section 6 and bent over upon the web of the 70 section 7 to secure the webs to each other.

The side flanges 9 of the sections 6 and 7 are return bent inwardly and have the transverse portions 13, the return bent portions 14 extending substantially parallel to 75 the outer faces of the flanges 9 and the end transverse portions 15. The return bent portions 14 are preferably provided with the apertures 16. The transverse end portions 15 and the return bent portions 14 are 80 adapted to engage the partition members, and as shown in Figure 2, these portions of the section 6 engage the flange 16 of the window sash 4. Suitable clips 17 are secured to the web 10 of the section 6 and 85 adapted to engage the side of the flange 16 opposite the return bent portion 14 to retain the sash in engagement with the return bent portion 14. 18 is a cover plate overlapping the side flanges 8 of the cooperating 90 sections and secured thereto as by means of the machine screws 19. This cover plate has at its edges the transverse side flanges 20 which extend inwardly and have the offset end portions 21 for engaging the end 95 of the flange 22 of the window sash, and the side of the wall panel 3 opposite to that engaged by the return bent flange of the section 7. The space inclosed within the section 6 is accessible by removing the cover plate 18 and is suitable for electric 100 wires, etc.

As shown in Figure 3, the door jamb 5 has the portion 23 located outside the section 7 and abutting the transverse portions 13 and 20 and also has the flanges 24 extending within the mullion section 7, one of these flanges being adapted to lie adjacent to the return bent portion 14. The inwardly extending flanges have the struck out ears 25 110 engageable in the apertures 16 in the return bent portions 14 for holding the jamb in

place. The offset portion 21 of the transverse flange 20 of the cover plate 18 also engages in the recess 26 formed by bending the flange 24. These flanges are identically shaped so that the door jamb is reversible to permit of swinging the door in opposite directions.

For securing the mullions 1 and 2 to each other, there is the angle strip 27 having the flanges 28 and 29 which lie adjacent to the webs of the horizontal and vertical sections 7 and 6 respectively. Suitable apertures are provided in the flanges of this angle strip and for securing the flange 28 to the mullion 15 there are the bolts 30 which pass through the elongated apertures 11 in the web of the section 7 and also the elongated apertures formed by striking out the tongues 12 in the web of the section 6. This flange is preferably secured to the mullion before assembling the mullions in the partition, while the flange 29 is secured to the vertical mullion 20 when assembling the partition. For securing the flange 29 to its web the T-shaped members 31 are provided passing through the webs of the sections and through the apertures in the flange 29, these T-shaped members having apertures through their stems which are engageable in by the wedges 32. With this arrangement to take down the partition, it is merely necessary to remove the cover plate 18 of the vertical mullion 2 and drive the wedges 32 out of place. The partition members such as the window, 35 door jamb and wall panels may also be disengaged when the cover plate is removed.

For the purpose of providing a construction which will be neat in appearance and will at the same time fit inaccurate floors, I 40 preferably secure a wood insert 33 to the floor as shown in Figure 5 and to this secure one of my standard mullion sections 34 to which is secured the cover plate 35. 36 are plates secured to the wood insert 33 as by 45 means of the screws 37 which plates overlap the cover plate 35 and the opposite side of the mullion section 34 a sufficient distance to permit of inaccuracy in the floor or wooden insert. Another feature shown in Figure 5 50 is the tying of the wall panel 38 to the return bent portion 39 of the mullion section return bent flange, the tying means being preferably a piece of wire 40 engaging the metal lath 41 of the wall panel.

55 As shown in Figure 6, the construction of mullion is identical to that shown in Figures 2 and 3 with the exception that panels of wood and glass 42 and 43 respectively are engaged.

60 What I claim as my invention is:

1. The combination with a partition member, of a mullion section having side flanges and a connecting web, one of said side flanges being return bent and engageable with one 65 side of said partition member, and a cover

plate secured to the other of said side flanges for securing said partition member against said return bent flange.

2. The combination with a partition member, of a mullion section having side flanges 70 and a connecting web, one of said side flanges being return bent inwardly and engageable with one side of said partition member, and a cover plate overlapping the other of said side flanges and provided with a transverse 75 inwardly extending flange for securing said partition member against said return bent flange.

3. The combination with a partition member, of a mullion section having side flanges 80 and a connecting web, one of said side flanges being return bent and engageable with one side of said partition member, a clip secured to the web of said section to retain the partition member in engagement with the return 85 bent flange, and a cover plate secured to the other of said side flanges for securing said partition member against said return bent flange.

4. The combination with a pair of cooperating mullion sections having adjacent webs secured to each other, and oppositely extending side flanges, the corresponding flanges at one side being return bent, partition members 90 engageable therewith, and a cover plate 95 secured to the corresponding flanges at the opposite side and having portions for maintaining said partition members in engagement with their respective return bent flanges.

5. The combination with a partition member, of a mullion section having side flanges and a connecting web, one of said side flanges being return bent and having an aperture in its return bent portion, said return bent 105 flange being engageable by said partition member, means extending through said aperture for positioning said partition member relative to said return bent flange, and a cover plate upon the other of said side flanges 110 having a transverse portion extending inwardly into engagement with the opposite side of said partition member.

6. The combination with a mullion section having substantially parallel side flanges and a connecting web, one of said side flanges being return bent, of a movable and reversible door jamb having a portion outside said mullion section, and a portion extending therewithin adjacent to said return bent flange, 115 and a cover plate detachably secured to the other of said side flanges and provided with a portion for securing said door jamb in place.

7. The combination with a mullion section having substantially parallel side flanges and 125 a connecting web, one of said side flanges being return bent, and having an aperture in its return bent portion, of a door jamb detachably and reversibly secured to said mullion section and comprising a portion outside 130

of said mullion section and portions extending therewithin, one of said inwardly extending portions lying adjacent to said return bent portion of the side flange and having an ear engageable in said aperture, and a cover plate detachably secured to the other of said side flanges and provided with a transverse inwardly extending portion engageable with the other of said inwardly extending portions of the door jamb to position the latter in place.

8. The combination with a horizontal mullion and a vertical mullion, of means permanently secured to the horizontal mullion and detachably secured to the vertical mullion for holding the same in fixed relation to each other.

9. The combination with intersecting mullions each comprising cooperating channel shaped sections having adjacent webs, said webs being provided with elongated apertures extending longitudinally thereof, of an angle strip having flanges extending adjacent to the webs of one of the mullion sections of each mullion, means extending through said elongated apertures and through one of said angle strip flanges for securing the same thereto, and wedging means extending through said elongated apertures and the other flange of said angle strip for adjustably securing the same to each other.

In testimony whereof I affix my signature.
JOHN SCHURMAN.
